UNITED STATES PATENT OFFICE

2,584,797

WALL WITH SOUND ABSORBING MATERIAL
POSITIONED BEHIND AN ARRAY OF
SOUND REFLECTORS

Ernest Thomas Fisk, London, and Alexander Wood, Cambridge, England, assignors to Electric & Musical Industries Limited, Hayes, England, a company of Great Britain

Application December 20, 1946, Serial No. 717,376
In Great Britain November 24, 1945Section 1, Public Law 690, August 8, 1946
Patent expires November 24, 1965

2 Claims. (Cl. 181—30)

1

This invention relates to sound recording or broadcasting studios, concert halls, music rooms or the like, hereinafter referred to as "studios."

It is found with such studios that the frequency range over which substantially faithful reproduction can be obtained has an upper limit of the order of 5000 cycles per second, owing to the natural sound absorbing properties of the studio walls or ceiling or due to the provision of sound absorbing material which serves to prevent reflections occurring, and consequently the sound is lacking in the higher frequency response, if it is desired that substantially faithful reproduction be obtained extending up to about 15,000 cycles per second.

The object of the present invention is to improve the frequency response characteristics of studios with a view to obtaining a more faithful reproduction extending over a wider frequency range than heretofore.

According to the present invention, in a studio sound reflectors are provided so disposed and of such dimensions as to cause reflection of sound over a range of frequencies to be augmented, said reflectors causing, however, only negligible reflection at lower frequencies.

Said reflectors according to one embodiment of the invention may comprise polished metal or glass discs or the like, the diameters or equivalent dimensions of which are large compared with the wave length of the sound which it is desired to reflect or according to another embodiment of the invention said reflectors may comprise strips of wood or other suitable material, the width of the strips being chosen so as to cause the desired reflection of the upper frequencies. Said reflectors are adapted to cause the upper frequencies to be augmented by pure reflection rather than by choosing the dimensions of said reflectors so that they are resonant at particular frequencies.

Preferably the reflection co-efficient of said reflectors is higher than the reflection co-efficient of the studio walls or ceiling and preferably suitable sound absorbing material is placed behind said reflectors to absorb low frequency components which pass the reflectors so as to ensure that the higher frequency components are reflected to a greater degree than the low frequency components.

In order that the said invention may be clearly understood and readily carried into effect it will now be more fully described with reference to the accompanying drawings, in which:

Figure 1 illustrates diagrammatically sound 55 absorbing material such as felt, indicated by the reference numeral 2, may be disposed behind the discs so ensuring that the higher frequency components are reflected to a greater degree than the low frequency components. In this way the greater relative absorption of the higher fre-

2

reflectors according to one embodiment of the invention in which the reflectors comprise metal or glass discs, and

Figures 2 and 3 illustrate other embodiments 5 of the invention in which the reflectors comprise strips of wood or other suitable material.

As shown in Figure 1 the reflectors 1 are in the form of discs made of polished glass or metal, a large number of said reflectors being provided 10 to the dimensions of the particular reflectors being so chosen that together they serve to cause substantially uniform reflection over the desired frequency range to be augmented. Alternatively selective reflectors may be employed so as 15 to augment some frequencies to a greater extent than other frequencies. In one example a large number of glass discs of approximately $\frac{1}{4}$ " in thickness may be employed, said discs having diameters varying from 6" to 18". A disc of 20 such form of 15" in diameter affords a strong reflection at 8,000 cycles per second and by suitably choosing the sizes of said reflectors and their distribution throughout the studio the frequency response of the studio above 5,000 cycles 25 per second can be augmented up to the desired maximum of 15,000 cycles per second.

Said reflectors may be applied to the existing 30 walls and/or ceiling of a studio and they may be so oriented as to cause reflection of the sound in a desired direction such as towards a microphone. Furthermore, if desired, the distance of 35 said reflectors from the microphone and their distribution may be so chosen as to afford multiple reflections so as to increase the reverberation time at the upper frequencies.

In Figure 1 the discs 1 are shown as being arranged in vertical rows, the discs in one row being of a different size from the discs in another row. This however, is not essential since the 40 discs can be arranged in any desired manner. The discs are spaced from the studio walls or ceiling and are supported or suspended in any suitable rigid manner. With discs of glass or metal the reflection co-efficient will in general 45 be better than the reflection co-efficient of the studio walls or ceiling and hence the latter will absorb the low frequency components which pass the reflectors, although if desired suitable sound 50 absorbing material such as felt, indicated by the reference numeral 2, may be disposed behind the discs so ensuring that the higher frequency components are reflected to a greater degree than the low frequency components. In this way the greater relative absorption of the higher fre-

3

quietcy components which normally occurs in the absence of the invention is avoided.

Instead of employing reflectors of disc form, reflectors of other shapes may be employed. Furthermore, said reflectors may be mounted on panels or other suitable structures so as to form reflecting units, which units may be mounted on suitable castors whereby they can be readily distributed in desired positions throughout the studio.

Figures 2 and 3 of the drawings illustrate further embodiments of the invention in which reflectors are in the form of strips 3 of wood or other suitable material, the width of the various strips being chosen so as to cause the desired reflection of the upper frequencies. In the case, for example, where it is desired to extend the frequency range over which a substantially faithful reproduction can be obtained up to about 15,000 cycles per second, strips of wood 1" in thickness and 2", 4" and 6" wide can be employed, suitably secured to the walls and/or ceiling of a studio. Said strips 3 can be arranged in effect like panels at various parts of the studio walls and ceiling and preferably each panel comprises two sets of strips as shown in Figures 2 and 3, one set of strips being arranged behind the other and with the longitudinal axes of the strips disposed at right-angles to one another as shown in Figure 2 with one set of strips vertical and the other set horizontal or they may be arranged as shown in Figure 3. The front set of strips and the rear set of strips are arranged in contact with one another and may be secured together where they overlap. Said strips may be held in position on the walls or ceiling by securing them to a supporting framework 4 (Figure 3) or said strips may be directly secured to the walls or ceiling of the studio, said strips being disposed about three to six inches from the walls and ceiling. If the strips 3 are made of wood, such as deal, although other materials can, of course, be employed, the reflection coefficient of such material may not be sufficiently high to cause reflection to the desired extent, in which case suitable sound absorbing material is placed behind said strips, said sound absorbing material being indicated at 5 in Figures 2 and 3, so as to absorb low frequency components which pass the strips, thus ensuring that the higher frequency components are reflected to a greater degree than the low frequency components as aforesaid.

4

The strips of different width need not be arranged in any particular order; the strips are, however, suitably spaced apart from one another with the narrow and wider strips spaced with a constant spacing or with a varying spacing as may be found desirable.

Although the invention is particularly applicable to sound recording or broadcasting studios, it may also be applied to concert halls and the like to improve the quality of the sound heard by listeners therein.

We claim:

1. A room having walls adjacent which an array of sound wave reflectors is provided, said array comprising a plurality of reflecting surface elements of varying sizes oriented and arranged in a plurality of rows adjacent the walls of said room, the adjacent rows being spaced from each other and in non-contiguous relation, each row containing reflecting elements of only a single size, the dimensions of said reflecting elements being large compared to the wavelength of the particular sound waves which are desired to be reflected, the reflecting elements all being spaced from the adjacent wall of the room, and sound absorbing material positioned behind said reflecting elements, between such elements and the adjacent wall of the room.

2. A room in accordance with claim 1, wherein the reflecting elements are disc elements on the order of six inches to eighteen inches in diameter to reflect sound wave frequencies in the range of five thousand to fifteen thousand cycles per second.
